METHOD AND MACHINE FOR MAKING
PAPER CUPS

Walter E. Amberg, Chicago, Ill., assignor to Universal Paper Products Company, Chicago, Ill., a corporation of Illinois

Application April 27, 1938, Serial No. 204,672

21 Claims. (Cl. 93—36.2)

This invention relates to an improved apparatus and method for use in the manufacture of cone-shaped paper cups having pointed apices.

Heretofore in the manufacture of cone-shaped paper cups having pointed apices it has been customary, so far as known, to form initially a paper blank and subsequently to roll or wind the blank thus formed into the conical vessel. Inasmuch as cones can be wound in various manners the blanks assume different configurations, but in every instance of the prior art it has been customary to form a blank of some kind and subsequently wind it into a pointed conical cup. In some instances it has been customary to die cut cut blanks from paper and stack them one upon the other in a magazine from which they are fed singly to a pair of cup forming cones. In other instances it has been proposed to cut the blanks from a continuous strip of paper or web and to feed the blanks thus cut singly, one by one, to the cup forming cones. In all of these instances it has been customary to have a certain amount of waste which is produced either during the die cutting, the blank forming, or the cup forming operations. In the first of these instances the waste results from the paper between adjacent die cuts, in the second by the paper which is disposed between adjacent cup blanks and is rejected as surplusage, and in the third by the excess paper which is trimmed from the blank by means of a knife engaging with the base of one of the cones.

It has been stated that heretofore pointed conical cups are formed by rolling or winding the blank about one of the plurality of cone-shaped mandrels or formers. These instrumentalities are subject to numerous objections owing to various problems which arise in connection with their use. They must preferably be mounted for rotation at the exact same speed, they must be separated at some point to permit discharge of a cup, and various other problems arise which encourage the development of a machine and process which would eliminate the employment of one or both of them.

With the foregoing desiderata in view, the present invention includes, among its various objects and features, the following several which may be said to be of outstanding significance. First, the provision of an improved machine and process which eliminates the formation of a blank as a step precedent to the formation of a pointed cone-shaped cup. By eliminating the necessity of pre-forming a blank obvious savings in cutting and material and accordant simplicity

in design of machines may be effected. This feature or object of the invention is accomplished by supplying to the machine a continuous strip of paper and winding or rolling a cone-shaped cup having a pointed apex upon the end of the strip of paper without first severing a blank therefrom. The cup is wound directly on the end of the strip and after the winding operation is commenced and before it is completed the cup itself, as it is being wound, is severed from the end of the strip.

Second, the improved machine and process include a former or mandrel about which the pointed cup is wound, but they dispense with the necessity of providing a cooperating former or mandrel of the same configuration. Instead of providing a second rotating cooperating former the invention proposes to associate a smooth, stationary cooperating member with the conical former, thereby eliminating one of the moving parts heretofore considered essential in an operation of this type. In accomplishing this object or feature of the invention the conical former is rotated about its own axis, simultaneously moved through a circular orbit or path, and in so doing presses against a smooth fixed surface which serves as a bed or presser plate during the operation of forming the cup.

Third, another important feature of the invention resides in the formation of a completed cup during two revolutions of the conical former about its own axis. Actually, the former rotates about its own axis approximately three times as it moves once through its circular orbit or path, and during two of these revolutions the cup is formed and during the third it is discharged from the former. Previously in the formation of cone-shaped cups having pointed apices it has been necessary, owing to the configuration of the cup blank and the operation of the cup forming instrumentalities, to rotate the conical former about its own axis three or more times in order to produce a cup, and inasmuch as speed of operation is of primary importance in the manufacture of inexpensive paper cups the provision of a method whereby a cup is produced on each dual rotation of the former constitutes a distinct contribution to the cup making art.

Other objects and features of the invention will become apparent from a reading of the following specification in the light of the accompanying drawing, in which

Figure 1 is a top plan view illustrating somewhat diagrammatically the machine and method of the present invention;

Figure 2 is a view showing a cup being wound upon the former of Figure 1;

Figure 3 is a view of the former in discharge position;

5 Figure 4 is a view in front elevation of a cup constructed in accordance with the present invention; and

Figure 5 is a view in section of the cup former and cutting knife.

10 In the drawing the machine and method are purposely shown somewhat diagrammatically. The actual machines which have been constructed to embody the present invention are replete with details of design and construction which, 15 although useful, are not considered patentable, and hence they are not being disclosed or claimed herein. On the contrary, in this application only the basic, important and broadly novel features of the invention are being disclosed and claimed, 20 in order that the importance of such features will not be obscured or overshadowed by the inclusion of mere details of feeding mechanisms, gluing devices, gear arrangements, supports, stackers and the like. All of these latter named 25 instrumentalities are old and any mechanic skilled in the art can quickly and conveniently adopt and adapt them for the practice of the present invention.

Turning now to Figure 1, a continuous strip 30 of paper coming from a roll or other suitable source of supply is indicated by the reference numeral 10, and this strip is fed by a suitable mechanism to a forming cone 12. In actual operation the forward or breast edge 14 of the paper strip is fed into the position illustrated in Figure 35 1, in which its central point coincides with the pointed apex of the former 12, and when it reaches this position further feed of the paper strip is temporarily suspended while a cup rolling or winding operation takes place. As shown, 40 the apex of the former exactly coincides with the breast edge of the blank, although, if desired, the apex may be moved slightly within the body of the blank in the manner illustrated in United 45 States Patent No. 1,434,934, granted November 7, 1922 to Van Sant.

The conical cup former 12 rotates about its own axis and simultaneously moves through a circular orbit of which, in the construction illustrated 50 in Figure 1, the apex of the cone forms the center. In the position illustrated a mechanical latch or clamp 16, known in the art as a pick-up, engages the forward extremity 18 of the paper strip and, as the cone continues to rotate and 55 move bodily in its circular path, the forward end of the strip is wound about the cone 12. This winding operation starts the instant the pick-up 16 engages the extremity 18 of the paper strip and continues until the cone reaches the dotted 60 line position shown in Figure 1, in which the cup has been completely wound on the conical former. Of course, to prevent the continuous strip 10 from being torn or twisted it is necessary to sever the cup from the end of the strip and this is done 65 simultaneously with the cup forming operation.

As shown in Figure 5, the rear edge 20 of the conical former is sharpened to serve as a cutting knife and it cooperates with a cutting edge 22 formed on the forward extremity of a platform 24 70 across the upper surface of which the paper strip 10 is fed. The contour of the cutting edge 22 is arcuate and corresponds identically to the path followed by the cone edge during the course of its rotation about the table or smooth surface upon 75 which the cone-shaped former is mounted. Thus,

in operation the pick-up first grips the corner 18 of the blank and the winding or rolling operation commences. Shortly thereafter, the instant the point 30 is reached, the cone edge engages and cooperates with the knife edge 22 and thereby severs from the strip 10 the cup which is being wound about the conical former 12. As the cone continues to rotate the severing operation continues until the point 32 at the opposite extremity 10 of the cutting knife is reached, whereupon severance is complete, and thereafter until the cone reaches the dotted line position shown in Figure 1 the operation of the machine is merely that of completing the winding or rolling of the cup. Thus, the cup is severed intermediate of the winding operation. The instant the cone has reached the dotted line position of Figure 1 the cup, now 15 completely wound and in its finished state, is wrapped about the conical former 12, whereupon by means of any convenient stripping device such as compressed air, a movable tip or plunger forming the apex of the conical former, or a stripping wheel which engages the exterior of the cup, the latter is removed from the conical former to permit the former to reengage the end of the strip 20 which has been fed forward by the feeding mechanism during the cup stripping operation.

In Figure 1 is illustrated in principle what is perhaps the most compact and economical machine ever devised for manufacturing pointed 30 cone-shaped cups. During each dual rotation of the cone former 12 about its own axis and each movement of the cone about the orbit a cup is formed. A number of factors contribute to this 35 important feature of the invention which consists in forming a cup on each dual revolution of the cone. For example, if the completed cup had projections or parts which tended to separate away from the cup when finally wound, it would be necessary to roll the cup for a comparatively 40 prolonged period of time against a cooperating surface in order to iron down these projections and give the glue an opportunity to solidify before discharging the cup, otherwise it would tend to 45 spring apart and the cup would come open at the seam. However, by affording the large adhesive area which is indicated by the reference numerals 45 A, B and C in Figures 1, 2 and 3, the amount of adhesive and the extent of the blank adhered thereby is sufficiently great or extensive that any 50 tendency of the blank to spring apart is overcome during a dual revolution of the cone. Furthermore, the blank itself has been so designed and is so shaped that likelihood or tendency to 55 spring apart is reduced to a minimum. Thus, as illustrated in Figure 4, the only point where there is a tendency is at the tip or point D and this tendency is overcome because practically the entire surface overlying this tip, as represented by the shaded area in Figure 4, is coated with 60 adhesive.

No paper is wasted during the cup forming operation and each cup is formed by severing it from the strip along the same arcuate or circular line. Only one cone is provided and it rotates, first, about its own axis which coincides with the longitudinal axis of a shaft 40 upon which the cone is mounted, and second, simultaneously therewith, through a circular orbit or path of which the apex of the cone forms the 65 center and the dotted line 42 forms the circumference. It will be apparent that the apex of the cone need not coincide with the center of the circle through which the cone moves and that by removing the cone and changing slightly the 70 75

contour of the smooth immobile table or surface around which it rolls it will be possible to change the position and arrangement of the cone with respect to the table. Thus, by making the table 5 slightly conical the forming cone 12 may be moved outwardly away from the center of the table, in which condition the apex of the cone will no longer coincide with the center of the circular path but will be more or less off-set therefrom. The important feature of the invention 10 in this regard resides in eliminating one of the conical rotating mandrels and substituting therefor a smooth immobile surface which cooperates with a single rotary former. This is made 15 possible by mounting the former for simultaneous rotation about, first, its own axis, and second, along a circular path in the direction of the center of which extends the apex of the conical former.

20 Two further points regarding this invention may be emphasized. One is the small and restricted areas in which the instrumentalities of this invention must operate. The other is the fact that this invention is designed to produce 25 single piece vessels. In the first place, the invention is particularly adapted for making cone-shaped cups having side walls which converge at a relatively sharp angle, and particularly those in which the height of the cup as represented by 30 the reference numeral *h* in Figure 4 is not more than twice the diameter of the cup as represented by the letter *d* in Figure 4.

Secondly, this invention relates to vessels 35 formed from a single piece of material as distinguished, for example, from that type of cup in which a second, separate piece of material is necessary to form the bottom of the vessel. In this connection, it may be noted that while I have stressed the value of my method for the 40 formation of single-piece cone-shaped vessels having a pointed apex, my method of rolling a conical mandrel in an orbit is also particularly well adapted for forming single-piece conical vessels in which the end or bottom is flattened 45 compressed inwardly, inverted, blunted, or otherwise shaped. This may be accomplished, for example, by providing a conical mandrel having a receding tip or apex adapted to cooperate with an auxiliary member movable toward and away 50 from the end of the mandrel as the mandrel moves in its orbit, thereby shaping the end or bottom part of the cup in any desired manner as the cup is being formed. In this way single-piece cups may be formed having a flat bottom 55 an inverted apex, or a plurality of recesses therein.

It will be appreciated from the description that has been given that the cone-shaped former rotates continuously about its own axis and 60 moves continuously through the circular orbit. Furthermore, the cup rotates three complete times about its own axis each time it moves 65 through its circular path. During two of these rotations the cup is completely wound about the former and during the third the cup is discharged into a suitable stacking or conveying apparatus. Thus, it will be seen that during a cup forming operation the paper is wound about 70 an apex which is located at the center of the forward edge of the paper, or somewhat inwardly therefrom, and the relative position of the apex of the cup does not change during the cup forming operation. First the corner of the blank is gripped by the pick-up and the winding operation 75 commences. This winding operation con-

tinues until the cup is completely formed, whereupon the cup is discharged from the former while the latter is continuing its movement through the circular orbit or path. Thus, the cup is moving laterally at the time it is discharged. From 5 a somewhat different aspect it will be observed that the cup blank is laid out on the flat supporting surface and is wound into a cone while lying on this surface. The winding continues even after the cup has been formed, causing the 10 formed cup to roll about the surface into a discharge position and to be discharged while it is still rolling or rotating about its own axis. To facilitate the discharge a movable sector may be provided in the supporting surface, said sector 15 receding away from the end of the cup when the latter reaches discharge position. One further point is of outstanding importance and may be noted. In accordance with this invention, the paper being formed into a cup does not change 20 the direction of its central longitudinal axis with respect to the axis of the strip from which it is severed. So far as I am aware, all other methods of rolling a single-piece cone-shaped cup about a mandrel require such a change of direction and 25 hence it is impossible to simultaneously form and sever a cup by such methods.

Having thus described the invention, what I 30 claim as new and desire to secure by Letters Patent of the United States is:

1. That improved process of making a cone-shaped vessel having a pointed apex, which consists in forming the vessel by winding it upon the unsevered end of a continuous strip of paper and progressively severing the vessel from the 35 end of said strip as it is being wound.

2. That improved process of making a cone-shaped vessel having a pointed apex, which consists in forming the vessel by winding it upon the unsevered end of a continuous strip of paper 40 and simultaneously severing the vessel from the end of said strip as it is being wound.

3. That improved process of making a cone-shaped vessel having a pointed apex, which consists in forming the vessel by winding it upon 45 the unsevered end of a continuous strip of paper and simultaneously and progressively severing the vessel from the end of said strip as it is being wound.

4. That improvement in methods of making 50 cone-shaped paper drinking cups having pointed apexes, which consists in forming the cup on the unsevered end of a continuous strip of paper and simultaneously and progressively severing the cup from the strip by a line of severance extending transversely of said strip.

5. That improved process of making a cone-shaped paper drinking cup have a pointed apex, which consists in forming the cup upon the unsevered end of a continuous strip of paper and 60 completing the forming operation by a single severing operation.

6. That improved process of making a cone-shaped paper drinking cup have a pointed apex, which consists in forming the cup upon the 65 end of a continuous strip of paper and accompanying the forming operation by a single severing operation extending transversely of said strip.

7. That improvement in the paper cup making art which consists in rolling a bodily movable 70 former over the end of a continuous piece of paper to wrap the end of said piece of paper about the former into a cone-shaped cup having a leakproof apex.

8. That improved process of making cone- 75

- shaped paper drinking cups having pointed apexes, which consists in winding the cup upon the end of a continuous strip of paper and severing the cup from the strip during a period intermediate of the winding operation. 5
9. That improved process of making a cone-shaped paper drinking cup have a pointed apex, which consists in winding the cup upon the end of a continuous strip of paper and severing the 10 cup from the strip, said severing operation commencing subsequent to the winding operation.
10. That improved process of making a cone-shaped paper drinking cup have a pointed apex, which consists in winding the cup upon the end 15 of a continuous strip of paper and severing the cup from the strip, said severing operation being completed prior to the completion of the winding operation.
11. That improved process of making a single-piece cup which consists in winding the cup upon the end of a continuous strip of paper and progressively severing the vessel from the end of the strip as it is being wound. 20
12. That improved process of making a cone-shaped paper drinking cup have a pointed apex, which consists in completely forming the cup during not more than two rotations of a conical former about which the cup is wound. 25
13. That improved process of making a cone-shaped paper drinking cup having a pointed apex, which consists in winding the cup about a conical former while the latter rotates about its own axis and simultaneously moves through a circular orbit, the center of which orbit coincides with the apex of the cup. 30
14. That improved process of making a cone-shaped vessel having a pointed apex, which consists in winding it upon a conical former which continuously and simultaneously rotates in a 40 circular orbit and about its own axis, with the apex of the vessel coinciding with the center of the orbit.
15. That improvement in the process of making a cone-shaped vessel having a pointed apex, which consists in winding the vessel about its apex as a fixed point and discharging the vessel while the mouth thereof is moving in a circular path and the apex is still fixed. 45
16. An apparatus of the character described, comprising, in combination, a conical former having a pointed apex and a smooth immobile surface in cooperative relationship therewith, said former being adapted to rotate about its own axis and simultaneously to swing through an orbit of which the center coincides at all times with the apex of the former. 5
17. An apparatus of the character described, comprising, in combination, a conical former 10 having a pointed apex and a smooth immobile surface in cooperative relationship therewith, said former being adapted to rotate about its own axis and simultaneously to swing through an orbit. 15
18. An apparatus of the character described, comprising, in combination, a conical former having a pointed apex and a smooth immobile surface in cooperative relationship therewith, said former being adapted to rotate about its own 20 axis and simultaneously to swing through an orbit with the apex of the former pointed in the direction of the center of the orbit.
19. That improvement in methods of forming single-piece paper drinking cups the height of 25 which cups is not more than twice the diameter of the mouth thereof, which includes the step of rolling a conical former around a smooth immobile surface.
20. That improvement in methods of forming 30 receptacles from a continuous flexible sheet material, which comprises the step of simultaneously forming and severing said receptacle from said sheet along arcs of equal radii.
21. That improvement in methods of forming 35 single piece paper cups, the height of which is not more than approximately twice the diameter of the open mouth thereof, which includes the steps of applying adhesive to a sheet of material from which a cup is to be formed, delivering the 40 sheet into a position beneath the conical former and above the smooth immobile surface and thereafter rotating the former to cause the sheet to be wound about said former to complete the cup forming operation. 45

- shaped paper drinking cups having pointed apexes, which consists in winding the cup upon the end of a continuous strip of paper and severing the cup from the strip during a period intermediate of the winding operation. 5
9. That improved process of making a cone-shaped paper drinking cup have a pointed apex, which consists in winding the cup upon the end of a continuous strip of paper and severing the 10 cup from the strip, said severing operation commencing subsequent to the winding operation.
10. That improved process of making a cone-shaped paper drinking cup have a pointed apex, which consists in winding the cup upon the end 15 of a continuous strip of paper and severing the cup from the strip, said severing operation being completed prior to the completion of the winding operation.
11. That improved process of making a single-piece cup which consists in winding the cup upon the end of a continuous strip of paper and progressively severing the vessel from the end of the strip as it is being wound. 20
12. That improved process of making a cone-shaped paper drinking cup have a pointed apex, which consists in completely forming the cup during not more than two rotations of a conical former about which the cup is wound. 25
13. That improved process of making a cone-shaped paper drinking cup having a pointed apex, which consists in winding the cup about a conical former while the latter rotates about its own axis and simultaneously moves through a circular orbit, the center of which orbit coincides with the apex of the cup. 30
14. That improved process of making a cone-shaped vessel having a pointed apex, which consists in winding it upon a conical former which continuously and simultaneously rotates in a 40 circular orbit and about its own axis, with the apex of the vessel coinciding with the center of the orbit.
15. That improvement in the process of making a cone-shaped vessel having a pointed apex, which consists in winding the vessel about its apex as a fixed point and discharging the vessel while the mouth thereof is moving in a circular path and the apex is still fixed. 45
16. An apparatus of the character described, comprising, in combination, a conical former having a pointed apex and a smooth immobile surface in cooperative relationship therewith, said former being adapted to rotate about its own axis and simultaneously to swing through an orbit of which the center coincides at all times with the apex of the former. 5
17. An apparatus of the character described, comprising, in combination, a conical former 10 having a pointed apex and a smooth immobile surface in cooperative relationship therewith, said former being adapted to rotate about its own axis and simultaneously to swing through an orbit. 15
18. An apparatus of the character described, comprising, in combination, a conical former having a pointed apex and a smooth immobile surface in cooperative relationship therewith, said former being adapted to rotate about its own 20 axis and simultaneously to swing through an orbit with the apex of the former pointed in the direction of the center of the orbit.
19. That improvement in methods of forming single-piece paper drinking cups the height of 25 which cups is not more than twice the diameter of the mouth thereof, which includes the step of rolling a conical former around a smooth immobile surface.
20. That improvement in methods of forming 30 receptacles from a continuous flexible sheet material, which comprises the step of simultaneously forming and severing said receptacle from said sheet along arcs of equal radii.
21. That improvement in methods of forming 35 single piece paper cups, the height of which is not more than approximately twice the diameter of the open mouth thereof, which includes the steps of applying adhesive to a sheet of material from which a cup is to be formed, delivering the 40 sheet into a position beneath the conical former and above the smooth immobile surface and thereafter rotating the former to cause the sheet to be wound about said former to complete the cup forming operation. 45
